UNITED STATES PATENT OFFICE.

GASTON STROBINO, OF PATERSON, NEW JERSEY.

SOUND REPRODUCER.

Application filed October 29, 1926. Serial No. 144,986.

In my application for patent for a sound reproducer, Serial No. 74,276, filed Dec. 9, 1925, I have disclosed a sound reproducer of the type in which an elastic vibratory structure including a resonator is intermittently tensioned and thereby vibrated by electro-magnetic means thereon, such sound reproducer distinguishing from others in its class by said structure being normally tensioned and as thus tensioned holding the elements (electro-magnet and armature) of said means in operative relation to each other and by the presence of elastic means holding said structure thus normally tensioned. The object of the invention is to provide a reproducer which shall reproduce in more faithful imitation of the originals than ordinary reproducers or "receivers" sounds differing from each other through a wide range of frequency. In this application I claim one of the species of the invention set forth in said application Serial No. 74,276.

In the drawings.

Fig. 1 is a side elevation of a resonator-including vibratory structure embodying the invention;

Fig. 2 is a view of said structure as seen when viewed from the right in Fig. 1;

Fig. 3 is a plan of said structure with the resonator removed; and

Figs. 4 and 5 are views illustrating two modifications and in which the resonator appears in each case in section and the remainder of the structure in side elevation.

The vibratory structure including a resonator in the example illustrated in Figs. 1 and 2 is represented by the U-shaped elastic metal member 1, which may be a permanent magnet, and the resonator 2, preferably of wood, member 1 being suitably secured at 3 to the resonator so that it stands in a plane perpendicular thereto and so that one arm, 1^a, is therefore free to vibrate independently of the resonator: the arm 1^a will of course be the freer to vibrate if as little as possible of the other arm, 1^b, is damped, wherefore I form the latter arm with a projecting base, as shown, affording limited contact with the resonator.

Said structure is normally tensioned by elastic means, as thus tensioned holding the elements of the electro-magnetic means for intermittently tensioning it in operative relation to each other. In the present case this tensioning means is as follows: 4 is an elongated stiff elastic flexible piece here in

the form of a lever which is fulcrumed and thereby has a bearing on the set-screws 5 in a projection of the arm 1^a of member 1 so as to oscillate in the plane of member 1 and has its shorter arm 4^a bent toward arm 1^b of member 1 and its longer arm bent off in the same direction and preferably engaged in a notch 1^x of said member. An adjusting screw 6, tapped into arm 1^b of member 1, bears against the adjacent side of lever 4 at about the middle of its longer arm, and between this screw and the bent or closed end of member 1 another adjusting screw 7 is tapped into arm 1^a of said member and bears against the longer arm of said lever. The electro-magnetic means or actuator here includes two electro-magnets, either of which may be treated as the armature of the other, and the coils 8 thereof are respectively arranged on soft-iron pole pieces 9, one of which may be on the end of arm 1^b of member 1 and the other on the short arm of lever 4. Such coils may be arranged in a telephone or equivalent circuit and are electrically connected at 8^a. The power and efficiency of the device being described, which is designed for use especially in connection with radio apparatus where the operating current is weak, depend very largely on the tension developed in member 1, the fact that said tension is maintained by elastic means, and also on the possibility of nicely calibrating the gap or spacing between the elements of the electro-magnetic actuator. In effecting adjustment for these purposes the screw 7 may first be turned to press the longer arm of elastic lever 4 downward, which elevates its shorter arm and opens the gap, and then screw 6 turned to bow said arm between 95 screw 7 and fulcrum 5, which depresses its shorter arm and closes the gap. The present construction is such that adjustment can be effected so that for any given gap required between said elements the tension may be varied, or for any given tension the gap may be varied, and always the tensioned structure is held tensioned by elastic means. While it is of course an advantage that an instrument be afforded which, as herein shown, is self-contained, still this is not indispensable, for the invention also contemplates a system to be vibrated including the elastic flexible vibratory structure and means (as 4 and 6—7) to exert variable elastic flexing pressure thereon at either of two points thereof in substantially a common plane of

flexure, in combination with electro-magnet and armature elements arranged one on the part of said system which is moved on flexing said structure and the other on another 5 part of said system. And in this broad statement it is to be observed that it is not material that said means to exert pressure on said structure have its elasticity afforded by a fulcrumed or lever-like part (4), 10 though such a construction lends itself to a movement-together as against a movement-apart in forming the gap and also a very nice calibrating of the gap, which is necessary when the mechanism is used in radio- 15 reception, where very weak currents must be depended upon to energize the electromagnet.

In Figs. 4 and 5 I show two different applications of my invention to sound reproducers of the so-called "loud-speaker" type for use in connection with radio-receiving apparatus: Fig. 4: Two concavo-convex parts 10, as of suitable wood, bear against each other at their peripheries, being there 20 held together by the screw-bolts 11, which may be arranged at suitable intervals. The upper one has sound outlet means 12 and the lower one supporting legs 13, which may if desired be composed of the same material 25 as such resonator and thus form resonating extensions thereof. The member 1 is contained within the casing formed by these two resonators, being secured to the lower one. A screw 14 is secured to and extends 30 up from the otherwise free arm 1^a of said member through a suitable aperture in the upper resonator and on its upper threaded end is a knurled nut 15. Fig. 5: The parts 35 16 are formed the same as parts 10, and the member 1 is contained and secured in the casing they form the same as in Fig. 4; but here a turn-buckle adjustment 17 (comprising a nut screwed onto the adjoining ends of 40 reversely threaded screws one of which is fixed in arm 1^a of member 1 and the other of which bears against the upper resonator) is interposed between arm 1^a and the central point of the upper resonator 16, tending to 45 hold it tilted as shown (one or two of the 50 screw-bolts 18 which penetrate the peripheries of the two resonators being drawn up more or less tight and the others left loose or serving mainly as guides and to limit the 55 upward or opening movement of the upper resonator), and there is means to draw the upper resonator downward consisting of a screw 19 in the lower resonator penetrating the upper one and having a thumb-nut 20 bearing on the latter.

60 In both cases the instrument contained in the casing formed by the two resonators may be pre-adjusted (as by the manufacturer) to such an extent that the user has only in Fig. 4 to turn nut 15 in the direction to pull 65 the arms 1^a and 1^b apart, or in Fig. 5 to

turn nut 20 in the direction to force said arms together, until the best sound-reproduction results; and when the mechanism is not in use a turning back of the nut will in each instance remove the strain from the 70 resonators so that they may be relaxed when idle and so will not become set from remaining in a strained state and lose their resonating quality. In my application Serial No. 88,835 I have disclosed a combination comprising an elastic vibrator (here afforded by 75 1-4-6-7), means to intermittently tension the same including electro-magnet and armature elements arranged thereon, said vibrator being yieldable to vary the gap between said elements, and adjustable means to cause such yielding of the vibrator and maintain the same in its thus-yielded state including a hollow shell housing the vibrator. But in that case said elements were 80 not adjustable independently of the means to cause yielding of the vibrator.

In Figs. 4 and 5 I note that each resonator gradually varies in thickness from a substantially central point in all directions to 90 its margin; in the present instance the construction is such that one of the extremes in thickness (i. e., its thinnest portion) is coincident both with its center and with the point of contact between it and what is in 95 effect a prolongation (14-15 or 17) of the member 1. In extensive experiments with resonators operated by a vibratory structure in contact therewith I have found that it is indispensable, in order to reproduce different qualities of sound in the one reproducing apparatus without adjustment thereof (for example, the low-pitched tones of the cello and the high-pitched tones possible with the violin) that the reproducer should have 100 105 this form.

Having thus fully described my invention what I claim and desire to secure by Letters Patent is:

1. In a sound reproducing apparatus, a 110 system to be vibrated including an elastic flexible vibrating structure and means for exerting variable elastic flexing pressure on said structure at either of two points thereof in substantially a common plane of flexure, in combination with coercive electro-magnet and armature elements arranged one on a part of said system which is moved on flexing of said structure and the other on another part of said system. 115

2. In a sound reproducing apparatus, a 120 system to be vibrated including an elastic flexible vibrating structure and means, wholly supported by said structure, for exerting variable elastic flexing pressure on said structure at either of two points thereof in substantially a common plane of flexure, in combination with coercive electro-magnet and armature elements arranged one on a 125 part of said system which is moved on flex-

ing of said structure and the other on another part of said system.

3. In a sound reproducing apparatus, a system to be vibrated including an elastic flexible vibratory structure, an elastic member carried thereby, and means, connecting said member and structure, for exerting variable flexing pressure on the latter, in combination with coercive electro-magnet and 5 armature elements arranged respectively on parts of said system of which one moves relatively to the other on flexing said structure.

10 4. In a sound reproducing apparatus, a system to be vibrated including an elongated elastic flexible vibratory structure, an elastic flexible lever fulcrumed therein, and means connecting said lever and structure and arranged to flex the former transversely of its 15 length, for exerting variable flexing pressure on said structure, in combination with coercive electro-magnet and armature elements arranged respectively on parts of said system of which one moves relatively to the 20 other on flexing said structure.

25 5. In a sound reproducing apparatus, an elastic flexible vibratory structure, an elastic flexible lever fulcrumed therein and means, connecting said lever and structure and arranged to flex the former, for exerting variable flexing pressure on said structure, in combination with coercive electro-magnet and armature elements arranged respectively on a part of said lever and a part of said 30 structure as to which the former part is movable relatively to the latter on flexing of said lever.

35 6. In a sound reproducing apparatus, an elastic flexible vibratory structure, an elastic flexible lever fulcrumed therein and separate means, connecting said lever with said structure at two points thereof in substantially a common plane of flexure, for exerting variable flexing pressure on said structure, in combination with coercive electro-magnet and 40 armature elements arranged respectively on a part of said lever and a part of said structure as to which the former part is movable relatively to the latter on flexing of said 45 lever.

50 7. In a sound reproducer, a bent elastic member, an elastic lever bearing against one extremity of said member and having a

pivotal support on the other, an electro-magnet and its armature carried one by the 55 first-named extremity and the other by said lever and opposed to each other, and means, connected with the lever remote from its bearing and pivoting points, to flex the same from one of said extremities toward the 60 other and thereby adjust the spacing between the magnet and its armature.

8. In combination, and elastic vibrator, means to intermittently tension the same including electro-magnet and armature elements arranged and one being adjustable thereon toward and from the other to vary the gap between them, said vibrator being yieldable to also vary said gap, and adjustable means to cause such yielding of the 70 vibrator and maintain the same in its thus-yielded state including a hollow shell housing the vibrator.

9. In combination, an elastic vibrator, means to intermittently tension the same including electro-magnet and armature elements arranged and one being adjustable thereon toward and from the other to vary the gap between them, said vibrator being yieldable to also vary said gap, and means 75 to cause such yielding of the vibrator and maintain the same in its thus-yielded state including a resonant hollow shell housing the vibrator and an adjustable connection between the vibrator and shell.

80 10. A sound reproducer including, in combination, a concavo-convex integral resonator shell formed to gradually vary in thickness from substantially the center thereof in substantially all directions to its margin, 85 and a vibrator having contact with the shell at one of its extremes of thickness, said shell being normally held by the vibrator in a state of flexing tension.

11. A sound reproducer including, in combination, an integral hollow resonating casing formed with a portion thereof gradually increasing in thickness in substantially all directions radiating from the same point and a vibrator contained in the casing and having contact with such portion at substantially said point and holding the casing normally in a state of tension.

In testimony whereof I affix my signature.

GASTON STROBINO.
